[57] **ABSTRACT**

The method comprises holding only one of two relatively movable tunneling machine portions against movement and displacing the other portion about a tunneling machine boring axis, and then holding only the other portion and corresponding displacing the one portion. The means comprise linkage members mutually joined and in which each one thereof is individually coupled to one of the machine portions, and means operative for effecting relative movement between the members.

ROLL ATTITUDE CORRECTING MEANS, FOR TUNNELING MACHINES

This invention pertains to a roll attitude correcting method, and means, for tunneling machines having a 5 rotatable cutter mounted to a first portion of a machine which is coupled to a second machine portion, said portions being relatively movable therebetween, and in particular to a method for displacing said portions relative to each other, sequentially, to effect the warranted correction, and to means intercoupling said portions operative for relatively displacing said portions.

Tunneling machines typically tend to gradually precess in a direction opposite to the direction of cutter 10 rotation and torque. This necessitates a periodic correction of the machine roll attitude in the tunnel by any one of several time-consuming procedures now practiced in the prior art.

It is an object of this invention to provide a method, and means, for effecting a roll correction, for a tunneling machine, of considerable magnitude in a minimum of time.

It is another object of this invention to teach means for correcting the roll attitude of a tunneling machine which has a cutter rotatable about a given axis and mounted to a first machine portion which is coupled to a second machine portion and in which said portions are relatively movable therebetween, comprising means for intercoupling said first and second portions operative for displacing said members relative to each other in a rotary direction about said axis; said coupling and displacing means including means operatively reactive from at least one of said members to effect said rotary displacement.

Further, it is another object of this invention to teach a method of correcting the roll attitude of a tunneling machine which has a cutter rotatable about a given axis and mounted to a first machine portion which is coupled to a second machine portion and in which said 40 portions are relatively movable therebetween comprising the steps of first holding only one of said portions against movement and displacing other of said portions relative to said one portion in a rotary motion about said axis; and then holding only said other portion against movement and displacing said one portion relative to said other portion in a rotary motion about said axis.

A feature of this invention comprises a method of holding one of two relatively movable machine portions against movement and displacing the other portion about the tunneling axis, and holding the other portion and displacing the one portion. The invention teaches means comprising linkage members mutually joined and in which each one thereof is individually coupled to one of the machine portions, with means operative for effecting relative movement between the members.

Further objects and features of this invention will become more apparent by reference to the following description taken in conjunction with the accompanying figures in which:

FIG. 1 is a plan view of a tunneling machine having a torque linkage members which embody the invention;

FIG. 2 illustrates the torque linkage members of FIG. 1 in outline form, and shows how they "fold" with cutter advance;

FIG. 3 is a rear elevation view of the torque linkage members and the pivot pin assembly which couples the members together;

FIG. 4 is an axial cross-sectional view of the pivot pin assembly of FIG. 3;

FIG. 5 schematically illustrates the pressured fluid supply means and valving for enabling operation of the invention; and

FIG. 6 is a fragmentary view of an alternate embodiment of a pivot pin assembly, according to the invention, shown in cross-section.

As shown in FIG. 1 a tunneling machine 10, including a pilot cutter 12, has a main cutterhead 14, and a cutterhead gearbox 16, and is, thus far, typical of what is known from tunneling machines in the prior art. The gearbox 16 provides rotary power for the cutterhead 14, and gearbox 16 and cutterhead 14 are advanced together, the cutter head being addressed to the face of the tunnel bore. The gearbox 16 has coupled thereto auxiliary jacks 18 operative for locking the gearbox 16 against movement by engaging the tunnel wall during re-cycling, or when otherwise needed for stability while not boring.

The machine further comprises a rib jack supporting frame 20 to which are coupled rib jack pads 22; these latter are operative for locking frame 20 against movement through engagement thereof with the tunnel wall. Fluid-power cylinders 24 are coupled to the gearbox 30, 35 16, by a thrust tube 25, through frame 20, and are operative for advancing the gearbox 16 and cutterhead 14, while fluid-powered cylinders 26 and 28, respectively, actuate the rib jack pads 22 and auxiliary jacks 18.

The tunneling machine 10, shown, to facilitate an understanding of the invention, comprises an extendable anchor assembly "A" which defines a pivot point about which the machine is steered. An anchor tube 27 extends axially of the machine from assembly "A" to a rear trunnion "RT." Steering of the machine is accomplished by vertical displacement of tube 27 by a vertical steering trunnion "VT" and/or horizontal displacement of the tube 27 by the cylinders 26. Machine thrust is transmitted from the cylinders 24 through the thrust tube 25 to the gearbox 16 and cutterhead 14. The thrust is reacted on a thrust reactor assembly 29 either through tension rods "R" to the rib jack pads 22 to the tunnel wall, or through the anchor tube 27 to the extended (anchored) anchor assembly "A" and to the wall of the pilot bore.

Between gearbox 16 and frame 20 there are disposed torque reaction linkage members 30 and 32. As shown in FIGS. 1 and 2 the linkage members are pivotally coupled together at 34 and the opposite ends of the members are pivotally coupled, at 36 and 38 to the gearbox 16 and frame 20, respectively. The purpose of members 30 and 32 is to communicate the rotary torque generated by the rotary cutterhead 14 to frame 20 which is locked to the walls of the tunnel.

In accordance with the teaching of this disclosure the members 30 and 32 are pivotally coupled together by means of a novel pivot pin assembly 40. In this embodiment of the invention, two linkage member assemblies and two pivot pin assemblies are arranged to either sides of the tunneling machine 10. Accordingly, one pivot pin assembly on the right-hand side of the

machine is denoted by the index number 40 and one pivot pin assembly on the left-hand side of the machine is denoted by the index number 40a. Both assemblies are substantially identical, except that one is turned 180° from the other. Linkage member 30 defines a yoke 42, shown in FIG. 4, which has limbs or bifurcations 44 and 44'; these limbs or bifurcations have bores 46 formed therein. Each bore has a liner 48; in these liners are received the ends 50 and 52 of a pivot pin 54. Cover plates 56 close one end of each of the bores 46 and cooperate with the pin 54 and the bores 46 to define therewithin variable volume chambers 58 and 58a. Each of the plates 56 has a fluid access bore 60 formed therein for admitting pressured fluid into chambers 58 and 58a.

Linkage member 32, which defines a pintle, has a bore 62 formed therein in which an intermediate portion of pin 54 is confined. The bore 62 of member 32 has a recess 64 formed therein which cooperates with a recess 66 formed in pin 54 to nest a ball-type bearing 68 therebetween. The recesses 64 and 66 and bearing 68, together with a bearing retainer 69 fixed at one end of bore 62, cooperate to prevent axial movement of pin 54 within linkage member 32, yet accommodates for an angular displacement between members 30 and 32. Pin 54 has two annular shoulders 70 integral therewith and extending therefrom which are disposed to engage the limbs 44 and 44' of yoke 42 to delimit the fluid-powered pin movement of the limbs 44 or 44' relative to member 32, and vice versa. Cup-type seals 72 envelope the inner walls of chambers 58 and 58a to prevent the leakage of fluid from the chambers.

In FIG. 5 is shown a schematic diagram of the fluid supply and valving system by means of which the novel invention is enabled. A source of pressured fluid 74 is communicated with a manual reversing valve 76 which has three distinct sections: conducting sections 76a and 76b, and intermediate closed section 76c. Source 74 communicates with valve 76 by means of a supply line 78, the fluid being conducted through the valve section 76a to a branched line 80. Branched line 80 communicates with line branches 82 and 84, in one positioning of valve 76, to supply pressured fluid to chambers 58 of each of the pivot pin assemblies 40 and 40a. A fluid reservoir 86 is through-connected with chambers 58a, via line branches 82' and 84' and branched line 80', in this one positioning of valve 76, to evacuate fluid from chambers 58a. Accordingly, when pressured fluid is admitted to the chambers 58, which are in 180° relationship, a cumulative effect results therefrom in which one or the other tunneling machine "portion" is rotated; i.e., the "portion" constituting gearbox 16, or the frame 20 "portion." For example, if rib jack pads 22 are locked against the walls of the tunnel, and auxiliary jacks 18 are retracted from the tunnel walls, and pressured fluid is admitted to chambers 58, then gearbox 16 will rotate about the axis of the tunnel a distance represented by the letter "Z" in FIG. 4. Conversely, to effect a corresponding correction of the roll attitude of frame 20, it is necessary only to retract rib jack pads 22 from the wall of the tunnel, engage jacks 18 with the wall of the tunnel, to lock the gearbox 16 thereto, and then address pressured fluid to both of the chambers 58a. This latter step is accomplished by putting valve 76 in the other positioning to admit pressured fluid, via

section 76b, to line 80'. Accordingly, the pivot pin assemblies 40 and 40a will effect a corresponding, roll correction of frame 20.

The embodiment of the pivot pin assembly 40 shown in FIG. 4 is one preferred structure. Other structures will occur to those skilled in the art taking a teaching from our invention. For instance, as illustrated in FIG. 6, an alternate embodiment of a pivot pin assembly 40' can be configured in which the annular shoulders 70 are dispensed with, and the cup-type seals 72 are not used. Instead a pivot pin 54a can be used which is disposed between a pair of floating pistons 87 which have a plurality of annular recesses or grooves 88 formed thereabout and in which are disposed seal rings 90 for fluid sealing of chambers 58 and 58a.

In the FIG. 4 embodiment, and in the "operative" positioning shown, a partial roll attitude correction of the machine 10 has been made as follows. Valve 76 was positioned to dispose section 76b in operation. Thus, chamber 58a was pressured and chamber 58 was evacuated. Assuming rib jack pads 22 to have been locked to the tunnel wall and jacks 18 retracted, gearbox 16 was rotated the "Z" distance. Cover plate 56, and the pressured chamber 58a reacted from the locked-in-place pin 54 and caused movement of limb or bifurcation 44' to move away from member 32. Consequently, bifurcation 44 moved toward member 32 — until it engaged the annular shoulder 70. To complete the roll attitude correction then, kind of complementary procedure is followed, to wit: rib jack pads 22 are retracted from the tunnel wall and jacks 18 are locked to the wall. Then valve section 76a is made operative, to pressure chambers 58 and evacuate chambers 58a. Now, pin 54 reacts from pressured and locked-in-place chamber 58 to cause member 32 to move away from bifurcation 44 and toward bifurcation 44' — until the latter is engaged by shoulder 70.

The embodiment of FIG. 6 depicts an "operative" positioning in which the admittance of fluid into chamber 58 has caused member 30' to move downwardly (relative to the illustration), presuming member 32 to have been anchored in place via jacks 22, or has caused pin 54a to move upwardly, presuming member 30' to have been anchored in place (via jacks 18). In this embodiment, the travel of the floating pistons (only one of which is shown) limits the amount of roll correction movement.

The dashed-line and angular positionings shown in FIG. 3 represents — if to some exaggeration, for purposes of visual aid — the provisioning made for an angular displacement, between members 32 and 30, by the ball-type bearing 68. Such angular displacement arises from the disparity between the members 32 and 30 when either the gearbox 16 or the frame 20 is rotated, about the tunneler's axis 92 to commence the roll correction. Normally, members 32 and 30 are in alignment with the axis 92 of the machine, but when (for instance) the frame 20 is first "roll-corrected," with the gearbox 16 locked to the tunnel wall, an angular displacement "A-D" occurs between members 32 and 30. Member 30, for being coupled to the gearbox 16, retains an alignment with axis 92; member 32, however, for being coupled to the "roll-corrected" frame 20, is displaced from axial alignment. Subsequent roll correction of the gearbox 16 conforms both members

32 and 30, again, to alignment with axis 92. Absent ball-type bearing 68, or some such similar structuring, this angular displacement could not be accommodated.

While we have described our invention in connection with specific embodiments thereof it is to be clearly understood that this is done only by way of example and not as a limitation to the scope of our invention as set forth in the objects thereof and in the accompanying claims.

We claim:

1. A tunneling machine, comprising:
first means for cutting relatively unyielding material;
second means coupled to said cutting means operative for rotating said cutting means;
third means coupled to said cutting means operative for forceably advancing said cutting means into said material; and
fourth means intercoupling said third means and at least one of said first and second means operative for effecting relative rotation between said third and said one means; wherein
said fourth means comprises means for receiving rotary torque reaction forces from said one means and transmitting said forces to said third means; and
said fourth means further comprises a plurality of doubled-ended linkage members, one half of the members of said plurality each being pivotally mounted at one end thereof to said advancing means, the other half of the plurality of members each being pivotally mounted at one end thereof to said one means; and further including
means pivotally joining the other end of each one of said members of said one half with an other end of one of said members of said other half.

2. A tunneling machine, comprising:

- first means for cutting relatively unyielding material;
second means coupled to said cutting means operative for rotating said cutting means;
third means coupled to said cutting means operative for forceably advancing said cutting means into said material; and
fourth means intercoupling said third means and at least one of said first and second means operative for effecting relative rotation between said third and said one means; wherein
said fourth means comprises means for receiving rotary torque reaction forces from said one means and transmitting said forces to said third means; and
said fourth means intercouples said advancing means and said rotating means, and comprises at least a first linkage member pivotally mounted at one end thereof to said advancing means, at least a second linkage member pivotally mounted at one end thereof to said rotating means, and means pivotally joining said first and second linkage members at the other ends thereof.

3. A tunneling machine, according to claim 2, wherein:

said joining means comprises a pivot pin assembly in penetration of said other ends of said linkage members.

4. A tunneling machine, according to claim 3, wherein:

one of said other ends defines a yoke having bifurcations, and the other of said other ends defines a pintle, said pintle is positioned between said bifurcations, and said pivot pin assembly is in penetration of said bifurcations and said pintle.

5. A tunneling machine, according to claim 4, wherein:

said pivot pin assembly includes a pivot pin having a longitudinal axis;
said pivot pin has an intermediate portion confined in said pintle and opposite ends thereof confined in said yoke.

6. A tunneling machine, according to claim 5, wherein:

said intermediate portion is secured in said pintle in a manner preventing relative movement, along said axis, between said intermediate portion and said pintle.

7. A tunneling machine, according to claim 5, wherein:

said pivot pin assembly further includes means disposed in said pintle securing said intermediate portion therewithin and preventing relative movement along said axis between said intermediate portion and said pintle.

8. A tunneling machine, according to claim 5, wherein:

said pivot pin assembly further includes means accommodating for rotary movement about said axis between said linkage members.

9. A tunneling machine, according to claim 5, wherein:

said pivot pin assembly further includes means accommodating for angular displacement, between said linkage members, about a point located on said intermediate portion.

10. A tunneling machine, according to claim 9, wherein:

said angular displacement means comprises a ball-type bearing interposed between said pivot pin and said pintle.

11. A tunneling machine, according to claim 5, wherein:

said pintle has a bore formed therein in which said pivot pin is disposed, and said bore has a recess formed therein at one end thereof;
said pivot pin has a recess formed therein which is juxtaposed with the recess in said bore; and further including
a ball-type bearing nested in said recesses; and
a bearing retainer fixed to said one end of said bore; said bearing, recesses, and retainer being cooperative to prevent relative movement, along said axis, between said intermediate portion and said pintle.

12. A tunneling machine, according to claim 5, wherein:

the bifurcations of said yoke each have a bore formed therein, the two bores being axially in line with each other and slidably receive said opposite ends of said pivot pin therein;
said bores each having means fixed at one end thereof for closing off said bores thereof;
opposite terminations of said pivot pin, said bores, and said closing means are cooperative to define variable-volume chambers therewithin.

13. A tunneling machine, according to claim 12, further comprising:

means selectively operative for supplying pressured fluid to, and for exhausting fluid from, said chambers to effect movement between said yoke and 5 pintle; and

means disposed between said pivot pin and said pintle preventing relative movement, along said axis, between said pin and said pintle.

14. A tunneling machine, according to claim 13, further comprising:

means confined within said chambers for sealing said chambers against leakage of fluid therefrom.

15. A tunneling machine, according to claim 14, wherein:

said sealing means comprise annular seals interposed between said opposite ends and said chambers.

16. A tunneling machine, according to claim 5, wherein:

said pivot pin has means, extending perpendicularly 20 from the longitudinal axis thereof, and spaced therebetween to either sides of said intermediate portion, for engaging surfaces of said yoke to delimit said relative rotation.

17. A tunneling machine, according to claim 16, wherein:

5

said delimit means comprise a pair of annular shoulders extending from said pivot pin.

18. Roll attitude correcting means, for a tunneling machine having first means for cutting relatively unyielding material, second means coupled to said cutting means operative for rotating said cutting means about an axis, and third means coupled to said cutting means operative for forceably advancing said cutting means into said material, said correcting means comprising:

means for intercoupling said third means and at least one of said first and second means operative for effecting relative rotation, about said axis, between said third and said one means; wherein

said intercoupling means comprises means for receiving rotary torque reaction forces from said one means and transmitting said forces to said third means; and

said intercoupling means further comprises at least a first linkage member for pivotal mounting at one end thereof to said one means, at least a second linkage member for pivotal mounting at one end thereof to said third means, and means pivotally joining said first and second linkage members at the other ends thereof.
